UNITED STATES PATENT OFFICE.

THOMAS H. SEELY, OF MALDEN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING-MACHINE.

1,372,782.

Specification of Letters Patent. Patented Mar. 29, 1921.

Application filed October 20, 1916. Serial No. 126,715.

To all whom it may concern:

Be it known that I, THOMAS H. SEELY, a citizen of the United States, residing at Malden, in the county of Middlesex and 5 State of Massachusetts, have invented certain Improvements in Lasting-Machines, of which the following description, in connection with the accompanying drawings, is a specification, like reference characters on 10 the drawings indicating like parts in the several figures.

This invention relates to lasting machines of the type employed for working a shoe upper over a last and securing it in over- 15 worked position by repeated operations of the machine along different parts of the shoe.

In machines of this type, the upper materials are gripped by pincer devices which 20 updraw or pull the materials to conform them to the last and then overdraw or carry the materials inwardly over the edge of the innersole, and a wiper is given movement to engage the upper materials and press or 25 wipe them smoothly upon the innersole into lasted position. The upper materials are then secured in lasted position by fastenings, which are fed or delivered to the action of 30 inserting mechanism. These operations are repeated successively on the different portions of the shoe.

During the lasting operation on this type of lasting machine, and during the driving of the fastenings or tacks, the shoe is 35 ordinarily held by both hands of the attendant while his foot maintains the starting and stopping treadle depressed to continue the machine in operation. When the attendant has finished lasting one shoe, he 40 places it upon a suitable rack or receiver and reaches for another shoe to be lasted. During this time it is expedient that the machine continue in operation, and in practice it is customary for the attendant to 45 maintain the starting and stopping treadle depressed. Loss of tacks is liable to occur at this time, because in the absence of means to prevent, the tack feeding or delivery means and inserting mechanism remain in 50 operation when there is no shoe in the machine.

In some machines of this general type, it has been proposed to suspend the operation of the tack-feeding means when a shoe is

not in position to be lasted, and in some 55 cases also, the inserting mechanism has, under such condition, been held in inoperative condition. In these prior machines the act of the attendant in placing a shoe in the machine has been utilized to determine the 60 delivery of tacks, and start the operation of the inserting mechanism. The means employed to this end has comprised some kind of a work rest, movement of which by the 65 shoe in the hands of the attendant was necessary, and devices of this character have been practically effective.

It is desirable in some cases, however, that the operative be relieved of the uncertain shoe positions and false motions that may 70 result where the effort of the operative is relied upon to initiate the tack delivery and tack driving functions, and an important feature of the present invention therefore, 75 consists in means movable by operation of the machine to detect the presence or absence of a shoe and suspend the delivery of tacks when absence of a shoe from lasting position is detected.

This feature of the invention is carried 80 into effect in the present instance by means of the wiper which advances over the edge of the shoe to press or wipe the upper materials into lasting position for the reception of a tack prior to each tack driving operation. Should a shoe be in position to receive a tack, wiper controlled means maintains the tack delivering or tack delivery 85 and tack driving means in operation, but should a shoe not be presented, as when the 90 attendant reaches for another shoe, the wiper-controlled means is caused to suspend the delivery of tacks, or the delivering of tacks and the operation of the tack driving means.

Another important feature of the invention consists in a yieldingly mounted wiper, which, as it moves over the shoe to perform its wiping action, presses yieldingly upon the upper materials to lay them to the last. 100 This aspect of the invention, in the present instance, is carried into effect by giving the wiper a movement or tendency to movement downward or in a direction toward the bottom of the last substantially at right angles 105 thereto as it moves over the edge of the shoe. If, at this time, a shoe is held in lasting position, the wiper will engage and press the up-

per materials down upon the innersole into lasting position as it wipes them inwardly, but should a shoe not be in position for the action of the wiper, the latter will still perform its wiping movement, but being no longer sustained by a shoe in the hands of the attendant, it will drop in response to its yielding tendency and effect a suspension of the tack delivering or the tack delivery and tack driving means.

Still another important feature of the present invention consists in the fixed work rest or support combined with means for suspending the tack delivering and tack driving operations when a shoe is not presented to the action of the machine.

The above features of the invention and others will hereinafter be described in connection with one good, practical form of the invention and then the several features will be made the subject of the claims.

In the drawings:

Figure 1 is a perspective view showing the fastening-inserting mechanism and the tack-delivering or feeding means, certain portions of the frame and other parts of the machine being omitted for clearness of illustration;

Fig. 2 is a side elevation with parts shown in section, illustrating more particularly the wiper control for the fastening-inserting and delivering means;

Fig. 3 is a view similar to that of Fig. 2, with the parts shown in different position;

Fig. 4 is a perspective view of the fastening delivery or controlling means looking upward from the side and front of the machine;

Fig. 5 is an enlarged detail, showing the driver lock and associated parts;

Fig. 6 is a plan view partly in section, showing the means for controlling the delivery of fastenings;

Fig. 7 is a view similar to that of Fig. 6, showing the relation of parts when the delivery of fastenings or tacks is suspended; and

Fig. 8 is a view similar to that of Figs. 6 and 7, with a part broken away, showing the relation of parts when a shoe is in the machine and a fastening or tack is to be delivered to the inserting mechanism.

Machines of the type illustrated are usually provided with pincer mechanisms which, under control of suitable actuating means, successively act upon different portions of the upper materials of a shoe to updraw and overdraw them relative to the last on which they have been previously assembled. In connection with the pincer mechanisms, there is usually associated a wiper for wiping or pressing the material onto the innersole in lasting position ready for the reception of fastenings. The pincer mechanisms are not shown in the drawings, because they

are well understood by those skilled in the art, and may be substantially as fully described in the U. S. Letters Patent No. 584,744, June 15, 1897.

The head frame 1 of the machine, only a portion of which is illustrated, may be of any suitable character for the support of the various operating portions of the mechanism, and mounted thereon for reciprocating movement, on each cycle of fastening-inserting operation, is the slide 2, technically known in the art as the tack carrier slide. This slide may be appropriately operated from any convenient moving part of the machine, or as fully illustrated and described in the patent hereinbefore mentioned.

Projecting from the tack carrier slide 2 is an arm 3, to the lower portion of which is appropriately secured in a well-understood manner, the tack carrier 4 having a passageway 5 for the reception of tacks in succession from a suitable raceway 6 or other convenient tack supply. Between the raceway 6 and the tack carrier 4 is the means for selecting tacks individually and in succession from the raceway, and delivering them singly to the opening 5 of the tack carrier. This selecting means may be of any usual well understood type, such, for instance, as illustrated in the patent to Cavanaugh, Jr., No. 873,018, December 10, 1907, and comprises a delivery table 7, Fig. 1, in which is mounted for reciprocating movement in front of the raceway 6, the separator 8. The table 7 and separator 8 may be of usual construction, and similar to the like parts shown and described in the patent to Cavanaugh, hereinbefore mentioned, the construction being such that when the separator 8 is reciprocated longitudinally in front of the raceway 6, it will select therefrom a tack and transfer it to the tack carrier 4 for delivery to the tack inserting mechanism. When a tack is thus transferred to the tack carrier, it is yieldingly held therein by the holders 9, of usual construction, so that as the tack carrier moves to tack-presenting position relative to the inserting mechanism, the tack will be prevented from dislodgment in the opening 5 of the carrier.

The fastening or tack inserting mechanism, in the present instance of the invention, comprises a driver bar 10 mounted for reciprocating movement in the head frame 120 of the machine. At the lower portion of the driver bar 10, is the driver 11 which engages the tack deposited in the opening 5 of the tack carrier and at appropriate time, forces the tack into the shoe presented for its reception. The driver bar 10 is normally under the influence of an appropriate driving mechanism, as for instance, such as shown in the patents hereinbefore called to attention. In the present instance, the 130

125

driver bar 10 is raised against its actuating spring by a cam 12, Fig. 5, mounted on the shaft 13 supported in the head frame 1 of the machine, the construction being such that when the driver bar 10 has been raised by the cam, and the cut-out portion of the cam passes below the usual projection from the driver bar, the latter will be forced downwardly to perform its driving function.

10 under the impulse of the usual operating spring as indicated in the patents mentioned, as well understood by those skilled in the art.

15 Adjustably secured to a bracket 14, Fig. 1, or to an appropriate portion of the head frame, is a block 15 carrying a work rest 16, against the end portion 17 of which the innersole of the shoe is held to position it for the tack-inserting operation. To assist 20 in thus positioning the shoe, there is mounted on the head frame of the machine, an edge gage 18 which may be of any appropriate character, but in the present instance is shown as an arm secured in fixed position 25 and having an edge against which the shoe may be pressed. The fixed work rest and edge gage 18 afford positive means for enabling the attendant to accurately position the shoe for the fastening or tack- 30 inserting action.

As hereinbefore noted, it is customary for the attendant to maintain the machine in operation after he has finished lasting one shoe, and while he is reaching for another. 35 During this interval, if the tack-delivering mechanism remains in operation, there will be, eventually, a loss of tacks, because no shoe is in the machine positioned to receive them. It is expedient that the operative be 40 relieved of the burden of starting and stopping the tack-delivering functions of the machine by his manual effort, and a practical means to this end consists of a wiper which, in addition to its wiping movement, 45 has an additional movement of which it may partake when a shoe is not in position to be lasted, and means are provided under the control of the wiper, to determine whether or not a tack shall be delivered or 50 fed to the tack carrier.

In the present instance of the invention, the wiper consists of a member 19 pivotally mounted at 20 on the tack carrier 4, and consequently partaking of the tack carrier 55 movement. When the tack carrier 4 is in its withdrawn position, to the right of Fig. 2, the wiper 19 moves over the top portion of the edge gage 18 and is maintained in its normal wiping position. As the tack 60 carrier 4 moves toward the shoe positioned by the work rest and the edge gage, it carries with it the wiper, which engages the upper materials and wipes or lays them onto the innersole into lasting position. If, however, 65 no shoe is presented for the action of

the wiper, the latter is free to partake of its additional movement, which in the present instance of the invention, is a falling or depressing action, and this additional movement of the wiper under such conditions is 70 utilized to stop the tack delivering operation, and preferably, though not necessarily, also, the tack driving operation, as will now be described.

Pivotedly mounted at 21 on the tack carrier, 75 is an arm 22, shown as of bell crank shape, and having a downwardly-projecting end portion 23 passing through a slot 24 of the tack carrier and normally resting on the top of the wiper 19. The upwardly-extending portion of the arm 22 bears upon a longitudinally-movable rod 25 normally under the influence of a spring 26, said rod and spring being mounted in the tack carrier slide 2, the construction being such that 80 should a shoe be in lasting position when the tack carrier slide, the tack carrier, and wiper move toward the shoe or to the left, Figs. 1 and 2, the wiper as it passes from the top portion of the edge gage 28 will 85 encounter the edge materials of the shoe and as it wipes them over the innersole into lasting position, will be prevented from turning about its pivotal mounting 20 under the stress of the spring 26; but should 90 the wiper 19 fail to encounter or detect the presence of the shoe in lasting position, it will drop into the position of Fig. 3 as it performs its wiping function, thereby permitting the spring 26 to move the rod 25 to the 95 left, Figs. 2 and 3.

To afford an adjustable connection between the rod 25 and the arm 22, the latter is provided at its outer portion with an adjusting device, such as the block 27, and 100 the adjusting screw 28.

The tack carrier slide is provided with a slot 29, in which is mounted the sliding block 30 interposed between the rod 25 and the spring 26, the construction being such 110 that the spring 26 acts upon the block 30 to move it longitudinally in the slot 29 when the wiper fails to detect and engage a shoe as it performs its wiping action.

To afford a convenient means for holding 115 the block 30 in its operative position and yet permit its ready removal when desired, there is mounted on the tack carrier slide 2 a swing plate 31 secured to the tack carrier slide by appropriate means, such as the 120 screw 32.

The tack carrier slide 2 has projecting from the side thereof, the lugs 33 between which is mounted a rocking member 34 by means of a bolt or other pivotal connection 125 35, the construction being such that the rocking member 34 will move with the tack carrier slide.

Pivotedly connected at 36 to the rocking member 34 is a link 37 pivotally connected 130

at 38 with a rocking segment 39 adapted to oscillate, as will hereinafter be described, about the stud 40. The rocking segment 39 has a series of teeth 41 in operative engagement with a corresponding series of teeth 42, formed in a segment 43 secured to the upwardly-extending shaft 44, Fig. 6, the construction being such that should the rocking segment 39 be turned contraclockwise, 10 Fig. 6, it will impart to the segment 43 a corresponding movement in the opposite direction and thereby turn the shaft 44.

The stud 40 has mounted thereon a sleeve 45 provided with a base portion 46 in which is formed a series of capstan holes 47, and from which projects the lug 48 carrying a pin 49 against which bears one end of a spring 50, the other end whereof at 51 rests against a lug or projection 52 extending 20 from the hub portion 53 of an arm 54 loosely mounted on the upright shaft 44. The rocking segment 39 is clamped to the sleeve 45 by suitable means, such, for instance, as the bolt 55, the construction being such that by 25 loosening the bolt 55, the sleeve 45 may be turned in appropriate direction by means of the capstan holes 47 to adjust the tension of the spring and its action upon the arm 54. To limit the relative movement of the 30 segments 39 and 43, a suitable stop may be employed as for instance, the adjusting screw 56, one end of which is adapted to contact with a lug 57 projecting from the rocking segment 39.

35 From the construction so far described, it will be apparent that when the tack carrier slide 2 moves in a direction to deliver a tack to the driving means, the rocking member 34 will be rocked about its pivotal 40 connection 35 with the tack carrier slide and the toothed segments 39 and 43 will remain in fixed positions. Should, however, the rocking member 34 be prevented from rocking movement as the tack carrier 45 slide moves to deliver a tack, it will cause rocking movement of the segment 39 in a contraclockwise direction, Fig. 6, into the position indicated in Fig. 7, thereby rocking the segment 43 and perforce, turning the 50 shaft 44 for a purpose that will presently appear.

The arm 54 has pivotally connected thereto, as at 58, a thrust member 59, the end 60 of which is normally pressed into a 55 recess 61 of an actuator 62 by the spring 50. The thrust member 59 is connected by a link 63 to the tack separator 64 which may be of usual construction as hereinbefore stated. The actuator 62 is pivotally 60 connected to the rocking member 34, and in the present instance of the invention, this pivotal connection is furnished by the bolt 65 which connects the link 37 to the rocking member, substantially as indicated in Figs. 65 6, 7 and 8.

The rocking member 34 has a toe or projection 65 which, in the normal operation of the machine when a shoe is in position for the lasting operation, misses the block 30 as the tack carrier slide moves the rocking member during the tack-delivering operation. The rocking member 34 has another toe or projecting portion 66 which, under the conditions noted, is adapted to engage an abutment 67 on the actuator 62 and cause 70 the said actuator to turn about its pivotal mounting 36 from the position indicated in Fig. 6 to that in Fig. 8, thereby, through the connections described, moving the tack separator 64 to take another tack from the raceway. On the reverse movement of the slide, that is to the right from the position of Fig. 8, a third toe or projection 68 on the rocking member 35 engages the actuator 62 at 69 to return the actuator to its initial 75 position, as indicated in Fig. 6, and effect the delivery of a tack.

Should, however, a shoe not be presented in lasting position for the action of the wiper as the latter performs its wiping 90 function, the wiper will not be held in its raised or wiping position, but will drop into the position indicated in Fig. 3, thereby permitting the spring 26 to move the block 30 into the path of the toe 65 on the rocking member 35. This contact of the toe 65 with the block 30 prevents rocking movement of the rocking member 34 as the tack carrier slide moves to the left to deliver a 95 tack to the inserting mechanism, as indicated in Fig. 7, and under these conditions the link 37 will cause the segments 39 and 43 to turn as hereinbefore described, to rock the shaft 44, for a purpose to be presently explained, and to prevent actuating movement of the actuator 62 sufficiently to operate the tack separator 64 and the parts 100 will then assume the position as indicated in Fig. 7, thus suspending the delivery of tacks.

Should the tack separator 64 be obstructed in its reciprocating movement during the normal operation of the machine, the thrust member 59 being held in the seat 61 of the actuator by the spring 50 will ride out of the seat 61 as the actuator performs its actuating function or swings from the position of Fig. 6 into that of Fig. 8. At such time, the end portion 60 of the thrust member will travel along the plane surface 70 of the actuator and a breakage of parts 115 will be prevented.

From the construction thus far described as one good, practical form of the invention, it will be apparent that when the wiper performs its wiping function and detects the presence of a shoe in lasting position, it will hold the block 30 out of the path of movement of the toe 65 of the rocking member 34 as the tack carrier slide and tack carrier 125

together with the wiper, perform their respective tack-delivering and wiping functions; but should the wiper detect the absence of a shoe from lasting position as it moves to perform its wiping function, it will no longer prevent movement of the block 30 into the path of the toe 65 of the rocking member 34, and the latter will therefore have its rocking movement arrested, and be carried bodily by the tack carrier slide to the left, without imparting to the actuator 62 operative movement sufficient to reciprocate the tack separator 64 and a suspension of tack-delivery will therefore occur.

It may be desirable in some cases, to arrest the operation of the tack-inserting mechanism when the wiper detects the absence of a shoe from lasting position. To this end, the shaft 44 has secured to the upper portion thereof, a block 71, Fig. 1, having an arm 72 connected to a driver lock 73, the toe end 74 of which is adapted to be projected under an abutment 75 of the driver 10, the construction being such that when the shaft 44 is turned clockwise from the position indicated in Fig. 6 to that of Fig. 7, at which time the wiper has detected the absence of a shoe from lasting position, the driver lock 73 will be moved into locking engagement with the driver 10. Obviously, the character of driver lock may be varied but in the present instance of the invention, it is shown as a rod mounted for sliding movement in a guideway 76, Fig. 5, at one side of the driver bar.

Normally the tack-delivering means and the fastener-inserting mechanism are operative to perform their respective functions, but are arrested in the discharge of these functions when the wiper detects the absence of a shoe from lasting position and will remain in such locked condition to suspend the delivery and driving of tacks until the attendant places a shoe in lasting position, whereupon the discharge of the functions of the tack delivering and driving mechanism is resumed.

What is claimed is:

50 1. In a machine of the character described, the combination of fastening inserting mechanism, fastening delivering means for delivering fastenings in succession to the inserting mechanism, means movable by operation of the machine to engage and act upon the work, and means controlled by the said movable means when it fails to engage the work to suspend the delivery of fastenings.

60 2. In a machine of the character described, the combination of fastening inserting mechanism, fastening delivering means for delivering fastenings in succession to the inserting mechanism, means moving automatically toward and from the work during

operation of the machine, and acting to suspend the delivery of fastenings when it fails to engage the work.

3. In a machine of the character described, the combination of a fixed work rest, fastening inserting mechanism, fastening delivering mechanism for delivering fastenings in succession to the inserting mechanism, and means moved to engage the work by starting the machine in operation and to suspend the delivery of fastenings when it fails to engage the work.

4. In a machine of the character described, the combination of fastening inserting mechanism, means for feeding fastenings to be inserted by said mechanism, a wiper for positioning the upper materials for the action of the inserting mechanism, and means controlled by the wiper for rendering the fastening feeding means inoperative when the work is not in fastening inserting position.

5. In a machine of the character described, the combination of fastening inserting mechanism, fastening separating and delivering means for delivering fastenings in succession for the action of the inserting mechanism, a wiper for positioning the upper materials for the insertion of fastenings, and means controlled by the wiper for stopping the delivery of fastenings when work is not present.

6. In a machine of the character described, the combination of a wiper for forcing the upper materials of a shoe into position to be secured, fastening inserting mechanism for inserting fastenings into the positioned upper, and means controlled by the wiper for suspending the operation of the fastening inserting mechanism when a shoe is not presented to the action of the wiper.

7. In a machine of the character described, the combination of a wiper for forcing upper materials of a shoe into position to be secured, fastening inserting mechanism, means for delivering fastenings in succession for the action of the inserting mechanism, and means controlled by the wiper for suspending the action of the inserting mechanism and delivery means when a shoe is absent from the machine during its continued operation.

8. In a machine of the character described, the combination of means for working an upper over a last, fastening inserting mechanism for inserting fastenings in succession, means for delivering fastenings into a position for insertion by the inserting mechanism, and means actuated by the overworking means in its movement for determining whether a fastening shall be delivered.

9. In a machine of the character described, the combination of means for working an upper over a last, fastening inserting mechanism for inserting fastenings, means for

delivering fastenings into a position for insertion by the inserting mechanism, and means controlled by the overworking means as it performs its overworking movement in 5 the absence of a shoe to suspend the operation of the fastening delivering means and the inserting mechanism.

10. In a machine of the character described, the combination of a tack-driver, 10 a tack carrier for presenting tacks to be driven by the driver, a tack separator for delivering tacks in succession to the tack carrier, a wiper for forcing the upper materials of a shoe into position to be secured, 15 and means rendered effective to suspend the tack delivering and driving operations by movement of the wiper when no shoe is engaged by the wiper.

11. In a machine of the character described, the combination of tack delivering 20 and tack inserting means, a wiper for forcing the upper materials of a shoe over the insole into securing position, and means associated with the wiper for permitting successive delivery and insertion of tacks while 25 a shoe is presented to the action of the wiper and operating to suspend the operation of the tack delivering and tack inserting means when no shoe is presented to the action of 30 the wiper.

12. In a machine of the character described, the combination of tack delivering and tack inserting means, a wiper having 35 a wiping movement and an additional movement and restrained from said additional movement during its wiping movement when a shoe is presented for treatment, and means controlled by the wiper for suspending the operation of the tack delivery 40 and inserting means when a shoe is not presented for treatment and the wiper makes such additional movement.

13. In a machine of the character described, the combination of tack feeding and 45 tack driving means, a wiper for forcing the upper materials of a shoe over the innersole into securing position, means acting yieldingly to press the wiper against the upper materials as it performs its wiping function, and means for suspending the feed 50 of tacks when the wiper fails to engage the work.

14. In a machine of the character described, the combination of tack feeding and 55 tack driving means, a wiper for forcing upper materials into securing position, means acting yieldingly to press the wiper against the upper materials of a presented shoe as it performs its wiping function, and 60 means rendered effective by movement of the wiper responsive to said yieldingly acting means when it fails to engage the work to suspend the operation of the tack feeding means.

65 15. In a machine of the character de-

scribed, the combination of tack feeding and tack driving means, a wiper, means tending to deflect the wiper out of the path of wiping movement as it moves in a direction toward the shoe and prevented from effecting such deflection by the presence of a shoe for treatment, and means for suspending the operation of the tack feeding and tack driving means rendered effective by deflection of the wiper when a shoe is not presented for treatment.

16. In a machine of the character described, the combination of fastening driving means, a carrier for presenting fastenings for the action of the driving means, 80 means for feeding fastenings to the carrier, a wiper for wiping the upper materials onto the bottom of the last, and means controlled by the position of the wiper as it makes its wiping movement for determining the operative or inoperative condition of the fastening feeding means.

17. In a machine of the character described, the combination of normally operative tack delivering and tack driving 90 means, a wiper for wiping the upper materials into lasting position, and means between the wiper and tack delivering and driving means for suspending the operation of the delivering and driving means when 95 the wiper in its wiping movement fails to engage a piece of work.

18. In a machine of the character described, the combination of a fastening inserting mechanism, fastening delivering 100 means for delivering fastenings to be inserted, a tool for operating on a shoe presented for insertion of fastenings, and means controlled by said tool for suspending the delivery of fastenings when the tool 105 in its operation fails to engage a shoe.

19. In a machine of the character described, the combination of fastening inserting mechanism, fastening delivering means for delivering fastenings to be inserted, a tool for positioning shoe materials 110 for the insertion of fastenings, and means controlled by said tool for suspending the delivery of fastenings when the tool, in its operation, fails to engage said materials. 115

20. In a machine of the character described, the combination of fastening inserting mechanism, fastening delivering means for delivering fastenings to be inserted, a wiper, means for moving the wiper 120 toward and from the work for wiping upper materials into position for the insertion of fastenings, means for moving the wiper in another direction, and means controlled by the wiper for suspending delivery of fastenings when the wiper is moved in said other direction.

21. In a machine of the character described, the combination of a wiper for wiping shoe materials into fastening position, 130

fastening delivering and inserting mechanism, and means actuated by the wiper in its movement for controlling the delivery of the fastenings.

22. In a machine of the character described, the combination of tack feeding and tack driving means, a wiper arranged for movement over a shoe bottom and for movement transversely of said movement, the wiper being retained in normal position against transverse movement by the work in position to be wiped, means for preventing the operation of the tack feeding and driving means, said means being constructed and arranged to be rendered ineffective by retention of the wiper in normal position and to be rendered effective by transverse movement of the wiper when such movement is permitted by removal of the work.
- 10 23. In a machine of the class described, the combination of tack feeding and driving means, a wiper carrier, a wiper arranged for movement relatively to the wiper carrier, and means for suspending operation of the tack feeding and driving means constructed and arranged to be rendered operative by said relative movement between the wiper and its carrier when in one direction and to

be rendered inoperative by said relative movement when in the other direction. 30

24. In a machine of the character described, the combination of means for securing a shoe upper, means for working the upper over its last, said means being constructed and arranged to be held in one position by contact with the shoe and movable from said position when not held by the shoe, and connections between the securing means and the overworking means constructed and arranged to cause the securing 40 means to be ineffective when no shoe is held to the overworking means.

25. In a machine of the class described, the combination of securing means, a tool movable in one direction to act on the work 45 and also movable in another direction by contact with the work, and connections between the securing means and the tool constructed and arranged to cause the securing means to be rendered operative when the tool is moved by contact with the work and to be rendered inoperative when the tool does not contact with the work. 50

In testimony whereof I have signed my name to this specification.

THOMAS H. SEELY.
